PAPER ROLL SUPPORTER

John Belloccchio, New York, N. Y.

Application October 28, 1932. Serial No. 639,941

9 Claims. (Cl. 242—68)

This invention relates to paper roll supporters. One object of this invention is to provide a device of the character described having improved means for supporting a plurality of articles such as paper rolls, in such a manner as to permit easy mounting and removal thereof one by one, as desired.

Another object of this invention is the provision of a device of the nature set forth having a few and simple parts, and which is inexpensive to manufacture, durable, reliable, and efficient in use.

Other objects and advantages of the invention will become apparent as the specification 15 proceeds.

In the drawing:

Figure 1 is a view in elevation of a device embodying the invention with a plurality of paper rolls applied thereto.

Fig. 2 is a similar view of the device in different position, certain of the paper rolls being removed.

Fig. 3 is a different view of the device in elevation without the paper rolls, shown in Fig. 2.

Figs. 4 and 5 are horizontal cross sectional views 25 taken on lines 4—4 and 5—5 respectively of Fig. 2.

Fig. 6 is a fragmentary view in elevation of a modification of the invention.

Fig. 7 is a horizontal cross sectional view there- 30 of taken on line 7—7 of Fig. 6.

The advantages of the invention as here outlined are best realized when all of its features and instrumentalities are combined in one and the same structure, but, useful devices may be produced embodying less than the whole.

It will be obvious to those skilled in the art to which this invention appertains, that the same may be incorporated in several different constructions. The accompanying drawing, therefore, is submitted merely as showing the preferred exemplification of the invention.

Referring in detail to the drawing, 10 denotes a device such as a paper roll supporter embodying the invention. The paper roll 11 or similar article may consist of a roll of tissue paper or the like which is usually wound upon a cardboard tube 12, and is to be considered as any conventional type. The device 10 may include a means such as 13 adapted to extend through the central openings afforded by the sleeves 12 of a plurality of paper rolls 11. Said means may have a plurality of movable spaced elements 14 for individually supporting the successive paper rolls, and the means 13 may have openings into which said elements are movable, so that the paper rolls are removable without any obstruction.

Thus the means 13 may consist of a plurality of elongated members or bars 15, 16 which are secured together at their ends in any suitable manner, as by spacers 17, and screws 18 threaded

into sleeves 18a fixed in one of the members as shown in Fig. 4, in a connection hereinafter described. A supporting means or hook 19 may be attached to the upper part 17 for carrying the device. Between the parts 17, the members 15 and 16 are spaced as shown.

The elements 14 may be in the nature of arms, which may have hubs 20, provided with stub shafts 21 journaled in aligned bearing recesses 22 of the members 15 and 16. Each arm and its stub shafts may be of one piece construction, and in this manner, the arms are mounted between the members 15, 16 so as to be movable into the space 23 therebetween. Each arm 14 is thus movable into a position to project laterally from the means 13, and into a different position to lie closely alongside thereof. In order to hold the arms in the projected position for supporting the paper rolls, any releasable or yielding engagement may be provided. Preferably, I utilize a frictional engagement of the members 15, 16 75 against the hubs 20 of the arms. For this purpose, I may provide a plurality of supplemental connections between said members in suitable relation to the arms. Thus screws 24 may be passed through said members for adjustably holding the same together, as with the aid of nuts or sleeves 18a. These screws 24 may be in relative proximity to the hubs 20 to assure a sufficient frictional engagement thereon.

Upon downward movement of the arms 14 into the space 23, the arms may engage stops 25 for limiting movement of the arms in said space. In order to facilitate removal of the arms from said space, recesses 26 may be provided in corresponding 95 positions in edges of the members 14, 15 to afford a finger hold on the element 14.

The arms 14 and the members 15, 16 may each or any of them consist of wood or metal, resilient or otherwise, and sheet material may also be employed. Preferably, the means 13 is of such size and shape in cross section as to suitably fill and guide the paper rolls.

The manner of using the device will now be described. A paper roll is received on the means 13 and moved upward from the lower to the upper end thereof, and an arm 14 adjacent to the lower end of the paper roll moved outward to support the same. This operation is repeated for each of the successive lower rolls until the device is fully loaded. Each arm is frictionally engaged between members 15, 16 so as to support the individual paper rolls. To remove one of the paper rolls, the lowermost thereof is grasped and pulled downward, the frictional engagement being thus overcome, and the arm affected entering the space 23 so that the roll can be removed without any obstruction, or hindrance.

In Figs. 6 and 7 is shown a modification of the invention including a means 13a having spaced

members 15a and 16a receiving arms 14. A stub shaft or trunnion 21a of the latter may extend through member 15a, and be provided on its end with a finger piece 26a, which, in order to avoid obstruction of a paper roll, may be located in a recess 26b of the member 15a. In this case, recesses 26 are unnecessary, and convenient manipulation of the arms 14 is obtained, the same being otherwise operative as hereinbefore described.

It will be appreciated that various changes and modifications may be made in the device as shown in the drawing, and that the same is submitted in an illustrative and not in a limiting sense, the scope of the invention being defined in the following claims.

I claim:

1. A paper roll supporter having means including a plurality of yielding elongated members disposed in spaced side by side relation to form a core upon which the paper rolls can be received, and a plurality of arms pivotally frictionally secured to said means at points spaced therealong for individually supporting the paper rolls, adjustable means urging the members toward each other for gripping said arms, said arms being movable into the space between said members for removal of the paper rolls from said means.

2. A paper roll supporter having an elongated means upon which a plurality of paper rolls can be consecutively received through the central openings thereof, said means having openings spaced therealong, arms pivotally frictionally secured in said openings and movable therefrom to project laterally from said means for individually supporting the paper rolls, said arms being movable into said openings for unobstructed removal of the paper rolls, and means yieldingly urging said arms into frictional engagement with the first mentioned means.

3. A paper roll supporter including means having a plurality of members spaced in side by side relation, said means being elongated so that a plurality of paper rolls can be consecutively threaded thereon, a plurality of arms pivotally connected to said means between said members so as to be individually movable into the space between said members and out of said space to project laterally from said means for individually supporting the paper rolls, and means for adjustably urging the members toward each other to engage said arms.

4. A paper roll supporter including means having a plurality of members spaced in side by side relation, said means being elongated so that a plurality of paper rolls can be consecutively threaded thereon, and a plurality of arms pivotally connected to said means between said members so as to be individually movable into the space between said members and out of said space to project laterally from said means for individually supporting the paper rolls, and means drawing said members together to engage and releasably retain the arms in said projecting position.

5. A paper roll supporter including means having a plurality of elongated members so that said means is adapted to receive a plurality of paper rolls through the central openings thereof, said members having a space therebetween, a plurality of arms pivotally connected to said means at points spaced therealong, means in proximity to the individual arms for drawing the same together to frictionally engage said

arms, said arms being movable to project laterally from said means for individually supporting the paper rolls, said arms being movable to lie in said space along said means for removal of the paper rolls from said means, and said arms being individually releasably engaged with said means in the projecting position mentioned.

6. A paper roll supporter including means having a plurality of elongated members so that said means is adapted to receive a plurality of paper rolls through the central openings thereof, said members having a space therebetween, and a plurality of arms pivotally connected to said means at points spaced therealong, said arms being movable to project laterally from said means for individually supporting the paper rolls, said arms being movable to lie in said space along said means for removal of the paper rolls from said means, and said arms being individually releasably engaged with said means in the projecting position mentioned, one of said members having recesses remote from the other member, and said arms having finger pieces for actuating the same, said finger pieces lying in said recesses.

7. A paper roll supporter including means having a plurality of elongated members so that said means is adapted to receive a plurality of paper rolls through the central openings thereof, said members having a space therebetween, and a plurality of arms pivotally connected to said means at points spaced therealong, said arms being movable to project laterally from said means for individually supporting the paper rolls, said arms being movable to lie in said space along said means for removal of the paper rolls from said means, and said arms being individually releasably engaged with said means in the projecting position mentioned, said members having recesses spaced along an edge of said means so that the arms may be individually manually engaged in said recesses for moving the arms from said space.

8. A paper roll supporter including means having a plurality of elongated members secured in spaced relation to each other to form a core upon which a plurality of paper rolls can be consecutively passed, a plurality of spaced elements pivotally secured to said means and frictionally engaged between said members so as to be adapted to individually support the paper rolls, said elements being movable into the space between said members for unobstructed removal of the paper rolls, stops to limit the movement of said elements between said members, and means spaced along the members and spaced from said stops for drawing the members toward each other for yieldingly engaging said elements.

9. The combination with a plurality of articles having openings therein, of means including a member successively extending through the openings of the articles, swingable elements mounted on said member at spaced points therealong for movement outward of the member so as to individually engage under the different articles for supporting the same, resilient means cooperating with said elements for frictionally retaining the same in said outward position, means connecting the resilient means with said member, and said elements being downwardly movable toward said member upon applying a downward force on said articles, so that the elements are movable through said openings, whereby the articles can be individually successively removed from said member.

JOHN BELLOCCHIO. 150
